Franklin H. Brown

FRANKLIN H. BROWN, OF CHICAGO, ILLINOIS.

Letters Patent No. 87,906, dated March 16, 1869.

IMPROVEMENT IN VENTILATORS FOR RAILROAD WATER-CLOSETS.

The Schedule referred to in these Letters Patent and making part of the same.

To all whom it may concern:

Be it known that I, FRANKLIN H. BROWN, of Chicago, Cook county, and State of Illinois, have invented a new and improved Ventilator for Water-Closets in Railway Passenger-Cars; and I do hereby declare that the following is a clear and exact description of the same, reference being had to the accompanying drawings, and to the letters of reference marked thereon, which form a part of this specification.

The drawing represents a vertical central section of my invention, clearly representing its various parts, and showing the direction of the currents of air by arrows.

To enable those skilled in the art to make and use my invention, I will proceed to describe its construction and operation.

I connect the wind-gatherer, or bonnet, D, to the common water-closet hopper, or casing B, by means of the pipe A, passing through the roof R of the car.

I also make one or more openings, x x, in the side of the casing B, underneath the seat E, and prefer them to be above the lower end of pipe A.

I mount the valve a a (in the common wind-gatherer) upon the shaft i and bearings g g, and the force of the wind causes it to shift from one to the other side of pipe A, as the car is made to move in one or the other direction.

I improve the valve a a by curving its upper sides out, as shown, forming a curved elbow, and thereby facilitating the passage of air from bonnet D to pipe A.

When the cars are set in motion, the air is forced in at D, down pipe A, through the casing B, and escaping at the bottom, as shown by the arrows.

Air will be drawn in from the room through openings x x, and thus the ventilation will constantly take place while the cars are in motion, whether the cover C be up or down, and the closet will be kept free from foul smells.

In the water-closets now in use upon railway-cars, the air is frequently forced up through the hopper, and into the room, while the cars are moving, making it offensive to persons in the closet or in its immediate vicinity, and very annoying to any one wishing to sit upon the seat.

F is the floor of the car.

Having thus fully described my invention,

What I desire to secure by Letters Patent of the United States, is—

The arrangement and combination of pipe A, hopper B, with its perforations, and wind-gatherer D, substantially as shown, and for the purpose specified.

Witnesses: FRANKLIN H. BROWN.
